SOCKET SLIDE

Daniel I. Reiter, New York, N. Y.

Original application June 23, 1931, Serial No. 546,179. Divided and this application April 14, 1932, Serial No. 605,137

12 Claims. (Cl. 24—77)

This application is a division of my co-pending application for patent for Self-adjusting fastener slide, Serial No. 546,179, filed June 23, 1931, now Patent No. 1,857,973, dated May 10, 1932.

5 This invention relates to pronged fastener slides and particularly, to that type which is provided with transverse slots for the reception of a belt or strap, and which carries a snap fastener element designed to engage a cooperating snap fastener element, in order to hold the strap carrying the slide to another article carrying said cooperating element.

10 My invention contemplates the provision of a simple and efficient ring socket slide adapted to be made of sheet metal, and to be readily assembled, and adapted for quantity production economically.

15 My invention further contemplates the provision of suitably arranged prongs on the slide for engaging the strap on which the slide is mounted, to fix the slide adjustably to the strap, as well as to another member carrying a cooperating snap fastener element. The various objects of my invention will be clear from the description which 20 follows, and from the drawing, in which,

25 Fig. 1 is a rear elevation of a socket slide embodying my invention.

Fig. 2 is a vertical central section of the same.

30 Fig. 3 is an elevational view of a blank from which the socket slide of Fig. 4 may be made.

Fig. 4 is a central horizontal section of Fig. 3 as it appears after the side projections or arms have been folded inwardly, and the resilient ring inserted thereunder to form the finished socket.

35 Fig. 5 is an elevational view of another form of blank which may be used for the socket slide wherein the side projections are somewhat narrower.

Fig. 6 is a view of the socket slide formed from 40 the blank of Fig. 5 and showing the laterally outstanding prongs thereon.

In the practical embodiments of my invention which I have shown by way of example, the slide is in each case preferably made of a single piece 45 of sheet metal, and is provided with opposed and spaced socket-forming elements, between which elements is arranged a suitable resilient ring forming the resilient socket member which cooperates with a corresponding stud. My improved socket slide is furthermore provided with suitable means so that it may be slidably mounted on a suitable belt or strap.

45 Referring now particularly to Figs. 1 and 2, I have there shown a slide member 10, provided 50 with spaced transverse belt-receiving slots 11 and

12 and with a substantially central opening 13. As illustrated, one of the transverse edges of each of the slots is provided with a suitable belt-engaging prong 14 projecting into the slot. It will be understood, however, that the prong 14 may be provided on the edge of only one of the slots, or that it may be entirely omitted, or that any desired number of prongs may be substituted for the single prong shown.

5 The resilient split stud-engaging ring 15 rests 10 against one of the faces of the slide member 10 and is confined in place on one side by means of the projecting side arms or extensions 16 and 17. Each of said arms or extensions is integral with and projects from an edge of the slide member, 15 and terminates in an arcuate edge as 18 which extends substantially to the median diameter of the ring 15, thereby preventing the ring from falling out through the opening 13.

The portion 19, of the socket opposed to the 20 arms 16 and 17, is formed by extending laterally the material of the slide member surrounding the opening 20. It will be seen that a suitably shaped stud may be inserted through either of the openings 13 or 20 in the slide into separable snapping 25 engagement with the resilient ring 15.

In Figs. 3 and 4, I have shown a slide similar to that shown in Figs. 1 and 2 and similar to that shown in Figs. 5 and 6. The blank 30 is provided with the spaced transverse slots 11 and 35 12, and is further provided with the projecting side arms or extensions 31 and 32. Said arms are sufficiently wider than the corresponding arms 16 and 17 of the slide of Fig. 1, to enable the formation of prongs 33 on the transverse edges thereof. At the outer longitudinal edge of each of said arms, a semi-circular portion as 34 is depressed 40 to form part of a ring-holding socket 35. Similarly, about the central aperture 13, the peripheral portion 36 is similarly depressed for the same purpose. The arms 31 and 32 are made of sufficient width so that the prongs 33 made on an edge of one or both of said arms, may project outwardly of the inner transverse edge of the corresponding slot.

45 After the arms 31 and 32 have been bent upwardly and inwardly to bring the respective recessed portions 34 thereof into proper registration with the recessed portion 36 and above the resilient ring 15 arranged between said recessed portions, it will be seen that a socket-carrying slide (Fig. 4) is provided wherein suitable prongs are adapted to engage a belt passed through the transverse slots 11 and 12, and wherein the cooperating stud may be passed in either direction 50 55

into the socket. It will be clear that the innermost edges of the recessed portions 34 and 36 in the finished slide are arranged substantially above and below, respectively, the median diameter of the ring 15. It will be understood that the prongs 33 may be omitted as illustrated in Fig. 1 or that such prongs may be arranged on one or more of the transverse edges of the transverse slots or that the prongs may be arranged to project laterally from the slide as illustrated in Fig. 6.

Referring now to Figs. 5 and 6, I have there shown, respectively, a blank 39 and a slide 38 similar to that shown in Figs. 1 and 2 excepting that the prongs 14 have been omitted at the transverse slots 11 and 12. In place thereof, laterally extending prongs as 40, 41, 42 and 43 on the arms 16 and 17 have been substituted. The arms are bent similarly to those described in connection with Figs. 1 and 2 to retain the ring 15 in place, and the prongs are bent laterally to project laterally from said arms. The arms have further been modified by slightly widening them so that they cover substantially all parts of the ring 15 and form a firm support therefor.

In any of the forms of slides illustrated, it will be understood that the belt or strap 45 is passed through the slots 11 and 12 and over the opening formed on one side of the socket. The belt is thus arranged in the proper position to be engaged by the prongs 14, 33 or 40 to 43 as the case may be, whereby the slide is secured in position on the strap. In certain cases, as for example, where the belt or strap is of sufficient thickness, the prongs may be omitted as is well understood. It will be seen that a suitable cooperating stud as 46 is suitably secured to the other belt or strap member 47 and that said stud, when passed into the socket, expands the ring 15 during the passage of the head of the stud, said ring contracting on to the neck of the stud to hold the stud in proper separable engagement therewith in the socket.

It will also be seen that the ring 15 is so arranged in the socket therefor, that the plane of the front face of the slide passes through approximately the center of the thickness of the ring, so that the ring is backed up against the walls of the socket when a lateral pull is exerted upon the slide.

It will be seen that I have provided a one-piece socket slide well adapted for economical manufacture and formed to hold a resilient ring therein in such a manner that a stud may be engaged with the ring from either side of the slide. It will further be seen that I have provided a socket slide well adapted to meet the severe requirements of practical use.

And it will be further seen that in each of the specific embodiments illustrated, the slide member may be of rectangular outline and have a pair of spaced transverse rectangular belt-receiving slots therein, that the stud may be engaged with the socket from either side or face of the ring and tilted out of the socket, and that the socket may have arcuate edges between which the ring is disposed, and that part of the socket as the part 19 of Figs. 1 and 2 or the part 36 of Figs. 3 and 4 comprises material extended or pressed laterally from the material of the slide member, and that in each of the embodiments illustrated, such extended part is bent from the contiguous material of the slide member through an angle not greater than 90°, and further, that such laterally extended material

is bent at its inner peripheral portion in a direction parallel to the remainder of the slide member. The slide member in each of the embodiments illustrated is imperforate between the juncture of the socket with the slide and the slots whereby greater strength results by reason of the lack of an opening between such juncture and the slots. It will also be noted that prongs may be provided on various parts of the integral slide member for the purpose of engaging a belt or strap passed through the pair of slots.

While I have shown and described certain specific embodiments of my invention, I do not wish to be understood as limiting myself thereto since I intend to claim my invention as broadly as may be permitted by the state of the prior art and the scope of the appended claims.

I claim:

1. In a socket slide, a one-piece slide member having a pair of spaced transverse slots therein and provided with a central opening between the slots, an arm bent transversely from and integral with the member, a socket-forming member integral with and bent laterally in one direction from the material of the slide member around said opening, a second socket-forming member integral with and bent laterally in the other direction from said arm, said socket-forming members being spaced apart laterally at their inner extremities to provide a recess therebetween, and a single resilient wire stud-engaging element having the outermost peripheral part of its surface arranged in the recess and the innermost remainder of its surface inwardly overhanging the recess, said element being arranged substantially coaxially of said opening.

2. In a socket slide, a slide member formed of a single piece of sheet metal, having spaced belt-receiving slots therein and having a stud-receiving opening between the slots, inwardly bent arms integral with the remainder of the slide member, prongs integral with the slide member and lying in the plane thereof and projecting into the slots, a continuous socket wall pressed laterally in one direction from a portion of the material of the slide member surrounding the opening, a similar continuous socket wall in lateral spaced relation to the first-mentioned socket wall and pressed laterally from each of the arms in the other direction, and a resilient ring arranged between said walls and retained in place thereby and inwardly overhanging said walls to engage a stud passed through the stud-receiving opening.

3. In a socket slide, a one-piece member provided with a pair of integral arms and forming a two-part ring-holding socket and provided with spaced rectangular belt-receiving slots, that portion of said member between the socket and the slots being imperforate, an undistorted resilient ring in said socket flat at its outermost circular elements, one part of said socket projecting beyond one face of said member a distance substantially equal to half the thickness of the ring and the other part of the socket projecting from said arms beyond the other face of said member the same distance, and said ring being arranged between said parts with the plane passing through the circular axis of the ring parallel to and between the faces of said member.

4. In a socket slide, a one-piece sheet metal member provided with a pair of integral arms arranged intermediate the ends of said member and bent inwardly toward each other and substantially parallel to the remainder of the mem-

ber to form part of a socket, the remainder of said socket being depressed from said member in a direction away from said arms, and a resilient ring in said socket.

5 5. In a socket slide, a one-piece sheet metal member formed of a blank having a substantially rectangular portion provided with spaced transverse belt-receiving slots and a central opening between the slots, an arm on the blank integral with each of the edges of the rectangular portion and terminating in an arcuate end, said arms being bent inwardly toward each other to arrange the arcuate ends of said arms in spaced relation to and in substantial alignment with the 10 edge of said opening, and a resilient ring arranged between the adjacent faces of said arms and the peripheral portion of said opening.

15 6. In a socket slide, a one-piece sheet metal member having a pair of spaced transverse slots therein and a circular opening between the slots, a ring-holding portion in said member surrounding the opening, a resilient ring resting against said portion, and an arm integral with said member and bent inwardly toward the opening at substantially right angles to an edge of the member, said arm terminating in an arcuate edge and being adapted to engage the ring to hold 20 said ring in place.

25 7. In a socket slide, a resilient undistorted ring, a one-piece sheet metal member provided with a pair of spaced transverse belt-receiving slots and with a circular opening between the slots, an arm integral with the member and bent from an edge thereof, a ring-holding socket having part thereof pressed laterally and outwardly 30 in one direction from the material of the member surrounding the opening a distance substantially equal to half the thickness of the ring and having the remainder thereof projecting laterally from the periphery of the arm in the other direction the same distance and formed from material integral with said member, the 35 ring being free to turn in the socket and a pair

of prongs each integral with the member and adapted to engage a belt passed through the slots.

8. An element of a separable fastener of the stud and socket type comprising a single piece of metal having attaching elements by means of which it may be directly secured to the article on which it is to be used and opposite marginal portions bent towards each other and provided with closely adjacent terminal portions so related as to jointly serve as an attaching element adapted for engagement with a complimentary fastener element. 10

9. A separable fastener element, as defined by claim 8, of which the attaching element at the 15 adjacent ends of the inturned portions is a resilient socket.

10. A separable strap fastener element comprising a single piece of metal having slotted portions by means of which it may be adjustably secured at any desired position on a strap and opposite marginal portions bent towards each other and provided with closely adjacent terminal portions so related as to jointly serve as an attaching element adapted for engagement 20 with a complementary fastener element. 25

11. A separable strap fastener element, as defined by claim 10, of substantially rectangular form, having its strap-receiving slots disposed along a pair of opposite margins and its attachment-forming portions bent under and inwardly 30 from its intervening margins.

12. A separable snap fastener socket comprising a single piece of sheet metal having slotted portions by means of which it may be adjustably secured at any desired position on a strap and a pair of oppositely-disposed inwardly-bent 35 marginal portions, the ends of said portions being closely adjacent each other and provided with semi-circular recesses adapted to cooperate with each other and serve as a socket for a complementary fastener stud. 40
